UNITED STATES PATENT OFFICE.

THOMAS C. ANTHONY, OF BROOKLYN, NEW YORK.

DESIGN FOR A DIRECTION INDICATOR FOR VEHICLES.

Application filed January 11, 1921. Serial No. 436,574. Term of patent 14 years.

To all whom it may concern:

Be it known that I, THOMAS C. ANTHONY, a citizen of the United States, and a resident of the city of New York, borough of Brooklyn, in the county of Kings and State of New York, have invented a new, original, and ornamental Design for a Direction Indicator for Vehicles, of which the following is a specification, reference being had to the

accompanying drawing, forming part thereof.

The figure is a perspective view of a direction indicator showing my improved new design.

I claim:

The ornamental design for a direction indicator for vehicles, as shown.

THOMAS C. ANTHONY.
